UNITED STATES PATENT OFFICE.

CHARLES HARVEY, OF SOMERVILLE, MASSACHUSETTS.

FUEL-OIL BURNER.

1,277,066.

Specification of Letters Patent. Patented Aug. 27, 1918.

Application filed April 8, 1918. Serial No. 227,163.

To all whom it may concern:

Be it known that I, CHARLES HARVEY, a citizen of the United States, residing at Somerville, in the county of Middlesex and State of Massachusetts, have invented new and useful Improvements in Fuel-Oil Burners, of which the following is a specification.

This invention relates to fuel oil burners, and has for its object to provide an oil burner adapted to vaporize fuel oil and utilize the same for cooking and heating purposes, a particular object of the invention being to provide a simple, strong and durable apparatus, free from liability to be warped or distorted by heat, and adapted to operate without objectionable noise.

The invention is embodied in the improvements which I will now proceed to describe and claim.

Of the accompanying drawings forming a part of this specification,

Figure 1 is a side elevation of an apparatus embodying the invention, one end portion of the apparatus being removed.

Fig. 2 is a section on line 2—2 of Fig. 1.

Fig. 3 is an end view of the apparatus, a portion being broken away.

Fig. 4 is a section on line 4—4 of Fig. 3.

Fig. 5 is a section on line 5—5 of Fig. 1.

Fig. 6 is a section on line 6—6 of Fig. 1.

Fig. 7 is a view similar to a portion of Fig. 4, showing a modification.

The same reference characters indicate the same parts in all of the figures.

The apparatus includes a base formed to contain a shallow body of oil to supply preliminary heat, said base comprising a horizontal bottom 12 and a marginal curb 13, projecting upwardly from the bottom, said bottom and curb forming portions of a shallow open tank or trough, adapted to contain a limited quantity of oil.

The base is provided with seats 14 which are preferably flush with the upper edge of the curb 13, and are adapted to support and be detachably secured to the angular member hereinafter described.

Said angular member includes spaced apart upright portions 15 and 16, constituting standards, and a horizontal intermediate tubular portion 17, constituting a retort, the said portions being preferably composed of cast metal formed as a single casting.

The bore 17^a of the retort communicates with the bore 15^a of the standard 15, said

standard being tubular. The bore 17^a is closed adjacent to the standard 16, as shown by Fig. 4, and the standard 16 is solid and serves only as a support for one end of the 60 retort. The standards 15 and 16 are attached to the seats 14 by bolts 18, as indicated by Figs. 5 and 6, said bolts passing through the seats and through slotted ears 19 formed on the lower ends of the standards.

20 represents an oil supply pipe, communicating with the lower end of the bore of the tubular standard 15.

A gas or vapor conduit having a vertical 70 portion 21 and a horizontal portion 22, communicates with the retort near the closed end thereof, the vertical portion 21 being connected with a nipple 23 formed on the retort, while the portion 22 extends under and 75 parallel with the retort, and is provided with a gas outlet 24 arranged to direct a flame upwardly against the flame spreader 25 formed on the under side of the retort.

Before operating the apparatus, a suitable 80 quantity of oil is supplied to the base, preferably through the supply pipe 20, the tubular standard 15, the retort, the gas conduit, and the outlet 24. If desired, however, the oil may be poured directly onto the base. 85 The oil on the base being ignited, preliminary heat is supplied, which vaporizes oil admitted to the retort. When a sufficient quantity of vapor has been generated, it constitutes the fuel supply and is ignited 90 at the outlet 24, the flame being directed upwardly against the spreader 25 and acting to continuously heat, not only the retort 17, but also the tubular standard 15 and the vertical portion 21 of the gas conduit. The 95 heating of the standard 15 and the gas conduit by the vapor flame is due to the fact that said standard and the conduit portion 21 are located at opposite sides of the burner outlet and in relatively close proximity 100 thereto, so that each receives heat from the laterally spread or deflected flame.

The angular form of the member which includes the standards 15 and 16, and the retort 17, and the attachment of the lower 105 end of each standard to the base, prevents any possibility of distortion of the said member, and displacement of the retort portion thereof, by heat, the retort being, therefore, maintained in a horizontal position 110 and at the exact height desired above the gas outlet 24.

The bottom 12 is provided with an up-standing tubular nipple 27, projecting through the oil confining space on the base, and constituting an inner oil curb surrounded by the marginal curb 13, and also constituting an air conduit extending through and above the base. The nipple 27 is provided at its upper end portion with a transverse channeled rest 28, which is preferably 5 U-shaped in cross section, as indicated by Fig. 2, the sides of said rest being separated from the adjacent sides of the nipple by vertical air passages 29. The rest 28 receives a part of the horizontal portion 22 10 of the gas conduit, and prevents downward and lateral displacement of said portion, so that the gas outlet 24 is maintained in a central position relatively to the spreader 25 and to the nipple 27.

15 It will now be seen that a flame directed upwardly from the gas outlet 24 induces an upward flow of air currents through the passages 29, the air mingling with the flame. The upper end of the nipple 27 constitutes a seat on which is detachably mounted a noise-reducing hollow cap, which includes a tubular body or wall portion 30, constituting an extension of the nipple 27 and provided with air passages 31, and a head 32 20 at the upper end of the body, and provided with a contracted central passage 33 for the flame and air mixed therewith. The lower end of the body is open, to receive the upper end of the nipple 27, and is provided 25 with ears or flanges 34 which bear on the seat formed by the upper end of said nipple. The tube or passage 33 is arranged so that the flame passes centrally through it. The said cap or nipple extension not only prevents objectionable noise when the burner is operating, but also prevents liability of accidental extinguishment of the flame. The extension is separably engaged with the nipple to permit convenient access to the gas 30 outlet 24, in case it is necessary to remove an obstruction from the outlet.

The base may be supported by a supplemental base 35, formed to bear on the grate of a fire-box, and open to permit air to pass 35 upwardly through the tubular wall 27. The burner when used in a stove or range having an oblong fire-box is preferably correspondingly formed, and made in two duplicate units arranged in tandem order, as indicated 40 by Figs. 1 and 4, the standard portions 16 being in close proximity to each other, and attached to the central portion of the base, which is made of sufficient length to support the two units. The elongated base may be 45 divisible at a point between the standard portions 16, to convert the structure into two independent, relatively short burners.

To this end the marginal curb 13 may include two transverse portions 13^a (Fig. 4), 50 at opposite sides of a narrow portion 12^a of

the bottom, said portion constituting a severable neck between two operative base portions, so that by sawing through, or otherwise severing said neck, two complete burners may be produced, each including elements such as the supply pipe 20, the angular member 15, 16, 17, and the gas conduit 21, 22, constituting an independent oil vaporizing and burning unit, adapted to operate as hereinbefore described. If desired, 70 the base may be formed in two sections, abutted together, end to end, and separably connected by bolts 37, or other suitable fastenings, as shown by Fig. 7, each section including a bottom portion 12^b and a continuous marginal curb 13^b, adapted to confine oil upon the bottom portion.

The channeled rest 28 constitutes a gutter, adapted to conduct oil, escaping from the outlet 24 to the oil-containing portion of the 85 base, said rest being preferably inclined as shown by Fig. 4, so that oil flows toward one end of the rest. Provision is thus made for preventing oil from falling through the air conduit formed by the nipple 27.

I claim:

1. An oil vaporizer and burner comprising a base formed to contain oil for preliminary heating, an angular member including spaced apart upright portions constituting 95 standards attached at their lower ends to the base, one of said standards being tubular, and a substantially horizontal tubular intermediate portion constituting a retort, and provided at its under side with a flame 100 spreader, the bore of said retort communicating at one end with the bore of said tubular standard, and being closed at the opposite end, and a gas conduit including an upright portion communicating with the bore 105 of the retort near its closed end, and a substantially horizontal portion extending under the retort and provided with a gas outlet, arranged to project a flame upwardly 110 against the said spreader, and an oil conduit connected with the lower end of the tubular standard, the said tubular standard and the upright portion of the gas conduit being at opposite sides of, and adjacent to, 115 said outlet and spreader, so that they are heated simultaneously with the retort, by the flame, the angular form of the said member, and the attachment of its two upright portions to the base preventing distortion of the member, and displacement of the retort portion thereof by heat.

2. An oil vaporizer and burner comprising a base having a bottom and an upstanding marginal curb whereby the base is adapted to contain oil for preliminary heating, 125 said bottom being provided with an upstanding tubular nipple constituting both an inner curb and an air conduit extending through the base, said nipple having a transverse channeled rest at its upper end portion 130

and air passages at opposite sides of said rest, a substantially horizontal retort extending over said nipple, means for supplying oil to said retort, a gas conduit connected 5 with the retort and extending into said rest, said conduit having a gas outlet centrally arranged relatively to the nipple, the upper end of the nipple constituting a horizontal seat, and a tubular nipple-extension resting 10 closely on said seat and removable therefrom to permit access to said gas outlet, said extension including a tubular body portion open at its lower end and having air passages, and a head having a central flame 15 and air passage located between the gas outlet and the retort.

3. An oil vaporizer and burner comprising a base formed to contain oil for preliminary heating, an angular member including

spaced upright portions constituting standards attached at their lower ends to the base, and a substantially horizontal tubular intermediate portion constituting a retort and provided at its under side with a flame spreader, means being provided for admitting oil at one end portion of said retort, and a gas conduit communicating with the opposite end portion of the retort and provided with a gas outlet arranged to project a flame upwardly against said spreader, the angular form of said member and the attachment of its upright portions to the base preventing distortion of the member and displacement of the retort and spreader relatively to the gas outlet by heat. 30 35

In testimony whereof I have affixed my signature.

CHARLES HARVEY.
